Patented Mar. 22, 1960

187,473

HOMOGENIZER

John B. McCabe, Fort Atkinson, and Alden H. Wake-
man, Lakemills, Wis., assignors to The Creamery Pack-
age Mfg. Company, Chicago, Ill., a corporation of Illi-
nois

Application October 26, 1956, Serial No. 43,539

Term of patent 14 years

(Cl. D23—1)

Fig. 1

Fig. 1 is a perspective view of the homogenizer showing our new design;

Fig. 2 is a front elevational view of the homogenizer shown in Fig. 1;

Fig. 3 is a right side elevational view of the homogenizer shown in Fig. 2; and

Fig. 4 is a top plan view of the homogenizer shown in Fig. 2.

The dominant features of the design are represented in full lines on the drawing.

We claim:

The ornamental design for an homogenizer, substantially as shown and described.
